UNITED STATES PATENT OFFICE.

BERT A. STOCKING, OF BOONE, IOWA.

WRINGER.

Application filed February 11, 1918. Serial No. 216,462.

To all whom it may concern:

Be it known that I, BERT A. STOCKING, a citizen of the United States, and residing at Boone, in the county of Boone and State of Iowa, have invented a certain new and useful Improvement in Wringers, of which the following is a specification.

This invention relates to washing machines and more particularly to a machine 10 of this character having a wringer attached thereto, and in which both the washing mechanism and the wringer may be driven from the same power shaft or separately by hand as desired.

15 Among the objects of this invention is the provision of a washing machine and wringer so combined that they may be simultaneously driven from the same motor shaft, or upon the simple manipulation of suitable control 20 elements both the washing machine and the wringer may be separately operated by hand; to provide such form of connection between the wringer and shaft which drives the washing mechanism that the wringer 25 rolls may be driven forward, backward, or thrown into position for operation by hand power; to provide means for automatically throwing the drain board into proper inclination for forward or backward rotation of 30 the rolls; to provide novel means for regulating the pressure between the wringer rolls; to so arrange the mounting of the wringer upon the washing machine platform that the wringer may be swung into and secured 35 in any one of a plurality of positions with relation to the tub, without disturbing its operative connection with the motor shaft in the least; to locate the driving motor entirely above the tub and other working 40 parts so that it will not be liable to injury through moisture from the tub, and will be conveniently located and easily accessible to the operator; to provide a pulley wheel on the drive shaft so that the washing mechanism 45 and wringer may be operated either by a motor located directly on the drive shaft, or by a belt from a separate source of motive power; to provide a novel form of means for holding the tub in tilted position while draining the water therefrom; to provide an improved form of stopper for the tub drain outlet; further to afford an improved form and arrangement of means 50 for selectively throwing the washing mecha-

nism into engagement for operation by motor power or hand power as desired.

The above and other features of advantages and capabilities become apparent from the detailed description of the accompanying drawings, in which I have illustrated a 60 device embodying my invention, but the construction there shown is to be understood as illustrative only, and not as defining the limits of my invention.

In the drawings:

Fig. 1 is a perspective view of a washing machine embodying my invention and showing the wringer in position for service to either tub.

Fig. 2 is an end elevation of the device 70 shown in Fig. 1 with the supplemental tub and platform being broken away and partly in section.

Fig. 3 is a side elevation of the machine 75 shown in Fig. 1, with parts in cross section for the sake of clearness.

Fig. 4 is an end elevation with the supplemental tub and platform removed and showing the wringer swung to a position at right angles with its position in Fig. 1; and parts 80 of the tub in cross section for the sake of clearness.

Fig. 5 is a vertical transverse section 85 through the column which carries the upright shaft.

Fig. 6 is a vertical transverse section through the wringer.

Fig. 7 is a plan view of the wringer with the drain board and reverse handle omitted.

Fig. 8 is a detail sectional view along 90 the line 8-8 of Fig. 6.

Fig. 9 is a detail view of the means for locking the wringer in any one of a plurality of adjusted positions.

Referring to the drawings: 1 designates 95 the stand which is provided with suitable legs 2, upon the bottom of which are mounted the casters 3. Detachably connected with the stand 1 by means of hooks 4 which take into apertures 5 along the edge of the stand 1 is the supplemental table 6, which is supported in horizontal position at its outer edge by suitable legs 7. Upon this supplemental table 6 is placed a supplemental tub 6', to be used in the obvious manner in conjunction with the washing machine tub 10.

Secured to the opposite edge of the stand

1 are the hinge ears 8 with which are pivotally connected brackets 9, which are in turn secured to the bottom edge of the tub 10. At one end of the stand 1 is the aperture 11, and adjacent this aperture and pivotally connected to the tub 10 is the bar 12, the pointed corner 13 of which when the tub is in tilted position enters the aperture 11 and firmly holds the tub in such position. It is obvious, of course, that a plurality of apertures 11 may be provided if desired, which would increase the number of positions to which the tub may be tilted and held. Upon the top of the hub is the usual lid 14, through which extends the shaft 15, upon the lower end of which is mounted for rotation therewith the usual dasher 16. To the upper end of the shaft 15 is suitably attached mechanism for rotating the same and comprising, located within the cover 17, a gear 18, see Fig. 1, which is rotated by means of a rack bar 19 attached to the upper end of the rocker arm 20 by means of a suitable pivot 21. Upon the upper end of the rocker arm 20 is also provided a handle socket 22 for use when it is desired to operate the washing mechanism by hand. Suitably mounted upon one side of the tub by means of screws, bolts, or the like, is a plate 23, which carries the bracket 24, and to which bracket is pivotally connected at its mid point the rocker arm 20. To each side of the plate 23 are suitably secured, as shown in Fig. 2, the respective ends of the hoop α , and upon which ends are suitable screw threads and nuts as shown for tightening said hoop around the tub.

Pivotally connected to the lower end of the rocker arm 20 is the connecting rod 25, the opposite end of which is pivotally connected with the end of the crank arm 26, which crank arm is mounted upon the end of the shaft 27, which is supported at the end adjacent the crank arm 26 by means of a bracket 28 secured to the under side of the stand. Rigidly secured to the opposite end of the shaft 27 is the gear 29, which in turn meshes with the worm gear 30, carried by the lower end of the upright shaft 31. The gear 29 is provided with the hub portion 32, one face of which has a clutch groove therein for engagement with a projection on the sleeve 33, rigidly mounted upon the shaft 27. It will thus be seen that this groove and projection form a clutch by means of which rotation is transmitted from the gear 29 to the shaft 27. Also formed upon the hub and upon that side of the gear 29 opposite to the clutch just described is an annular groove 34, slidably engaging with which is a bifurcated end of the arm 35, which arm is rigidly secured upon the rod 36 for movement therewith. Surrounding the gearing mechanism just described is the casing 37, which is adapted

to hold therein a suitable quantity of oil or grease in order to provide continual lubrication for the gearing therein. Within the casing 37 is the bearing 30', see Figs. 3 and 5, which furnishes a suitable support for the worm gear 30. The rod 36 is mounted at one end in the sides of the casing 37 which surrounds the gearing just described, and is supported at its opposite end in the bracket 38 secured to the under side of the stand 1. Rigidly mounted upon the end of the shaft 36 and adjacent the bracket 38 is the handle 39, upon which is formed the projection 40 for engagement with the notches 41 in the quadrant 42, by means of which notches the handle may be secured in any one of a plurality of positions as desired. From the mechanism just described, it will be seen that the gear 29 may be moved laterally upon suitable movement of the handle 39, which lateral movement of the gear will throw the clutch formed upon its hub 32 either into or out of engagement with its corresponding part on the shaft 27, which will result in the operation or not as desired of the washing mechanism, as will be apparent upon an inspection of the drawing.

Rigidly secured upon the lower end of the upright shaft 31 is the belt pulley 43, by means of which the shaft 31 may be rotated from a separate motor or other source of motive power if desired. Mounted upon the stand 1 is the upright column 44, through which column extends the upright shaft 31. The upper portion of the column 34 is counter bored as seen in each of Figs. 5 and 9, within which counter bore is located the sleeve 45, upon the upper end of which is secured the bracket 46, which bracket carries the wringer 47. Formed upon the upper end of the column 44 and adjacent the sleeve 45 is the extension 48, see Fig. 9, in which extension is pivotally mounted the lever 49, by means of the pivot 50. Projecting from each side of the lever 49 and slightly above the pivot 50 are the arms 51 and 52, the arm 51 of which projects through the aperture 53, and the inner arm 52 of which projects through the aperture 54, and fits into the socket 55 formed in the lower portion of the sleeve 45. Surrounding the arm 51 is a compression coil spring 50' whose normal tendency is to force the arm 52 into locking engagement with one of the sockets 55. A plurality of these sockets may be disposed around the circumference of the sleeve 45 for a purpose to be hereinafter disclosed.

As will be seen from an inspection of Fig. 1, the bracket 46 is in the form of a yoke, the two ends 56 and 57 of which engage the shaft 31 at spaced positions. Slidably keyed or splined to rotate therewith upon the shaft 31 and between the two ends 130

56 and 57 of the bracket 46 is the sleeve 58, which is provided upon one end with the right hand threads 59, and upon its other end with the left hand threads 60, between which threads is formed the depression 61. Mounted at the upper end of the shaft 31 is a suitable motor 62 to impart rotation as desired to said shaft. The gearing 59, 60, 68, 69, and 77 may be suitably covered with 10 a guard casing if desired.

Carried by the bracket 46 and suitably secured thereto is the wringer 47, which comprises rolls 63 and 64, which rolls are mounted at their ends in the uprights 65 and 66. 15 Slidably mounted upon one end of the wringer frame is the vertically arranged carriage or slide 67 which is operated by means of the rack 68, see Fig. 6, secured thereto, and the pinion 69 fixed upon the 20 end of the rod 70, which rod is rotatably mounted in the wringer frame and carries upon its outer end the handle 71, which handle is pivotally mounted thereto, in order that the same may be swung in or out for 25 seating into the slots 72 of the quadrant 73, mounted upon the end of the wringer. Within said quadrant and between the wringer frame and the handle 71 is the spring 74, whose function is to resiliently 30 hold said handle seated within the desired notch of the quadrant in an obvious manner. Formed integrally with one side of the carriage 67 are the bifurcated arms 75 and 76, which arms fit on each side of the shaft 31 and 35 over the ends of the worm sleeve 58, see Figs. 1, 4 and 7, by virtue of which it will be apparent that as the carriage 67 is moved up or down the sleeve 58 will have a similar motion imparted thereto. Secured upon the 40 end of the shaft of the roll 63 is the gear 77 which is of suitable diameter to engage with the worm teeth 59 or 60 on the worm sleeve 58 according as either of these worm teeth are thrown opposite the gear 77.

45 Fastened to the top of the sliding carriage 67 is the rod 78, as shown in Figs. 2 and 3, which rod extends outwardly and downwardly and at its lower end is bent laterally to engage with the projection 79 on the lower 50 portion of the drain board 80, which is tiltably mounted between the uprights 65 and 66 of the wringer frame, and located just below the roll 64, the function of which drain board is to carry away in an appropriate direction the excess water as it runs from the rolls. The roll 64 is resiliently mounted upon the springs 81 and 82, see Fig. 6, which are mounted beneath each end of this roll, and which springs bear respectively upon 55 the blocks 83 and 84, the under faces of which are provided with the bevelled portions 85 and 86 respectively. The blocks 83 and 84 are mounted within the uprights of the wringer frame so as to have a free up 60 and down motion therein, except as limited

by the springs 81 and 82 upon their upper portions, and by the bevelled faces 87 and 88 of the blocks 89 and 90 respectively on their lower faces. As shown in Fig. 6, the blocks 89 and 90 are engaged by means of 70 right and left hand screw threads with the shaft 91, which carries upon its outer end a hand wheel 92. By virtue of this right and left hand thread arrangement and the bevelled faces as shown, it will be apparent 75 that upon suitable rotation of the hand wheel 92, the blocks 89 and 90 will be moved in opposite directions, which will, because of the sliding contact with the bevelled faces, result in the upper blocks 83 and 84 being either raised or lowered according to 80 which direction the hand wheel 92 is turned. This will result in the springs 81 and 82 being either compressed or relieved of compression according to the direction of rotation of the hand wheel which in turn will make possible the desired adjustment of tension between the rolls 63 and 64.

Fastened by means of screws, rivets, or the like, to the blocks 89 and 90, see Fig. 8, 90 is the handle 93, which extends parallel with the rolls to the end thereof and thence upwardly above the top of the wringer frame. When the handle 93 is thrown back away from the wringer frame, the blocks 89 and 95 90 which, as above stated, are secured to the lower portion of this handle, will be abruptly rotated upon the shaft 91, and consequently quickly separated from contact with the bevelled faces 85 and 86, which will result in the blocks 83 and 84 moving downwardly under action of the springs 81 and 82, which will thus relieve the tension in said springs, and permitting the rolls 63 and 100 105 64 to be separated. This will be of special value should an article of clothing become tangled with the rolls during the wringing, or other accident take place. As seen in Fig. 6, the shaft 94 of the lower roll 110 115 64 extends outwardly through the slot 95 of the upright 65, which shaft has a squared portion or other suitable configuration formed upon its outer end for the accommodation of a handle for use when it is desired to operate the wringer by hand.

120 Inserted through the bottom of the tub 10 is the drain pipe 96, which has screw threaded or other suitable engagement therewith. Pivoted to each side of the drain pipe by means of pivots 97, see Fig. 2, is the angular link 98, the outer portion of which directly opposite the drain pipe is provided with the aperture 99, see Fig. 4, through which aperture extends the stem 100, upon the end of which is formed a valve 101, 125 which valve is adapted to fit in the valve seat 102. The stem 100 may have screw threaded engagement within the aperture 99, or it may have longitudinal motion imparted thereto by means of springs or other 130

- similar construction if desired. Upon the outer end of the stem 100 is the handle 103, by means of which the valve 100 may be readily placed against the seat 102 or removed therefrom. This construction results in an easily and quickly operated and exceedingly efficient stopper for use when it is desired to drain all of the water from the interior of the tub.
- 10 The operation of my improved device is as follows: Upon suitable movement of the handle 39 the gear 29 will be thrown into engagement with the worm wheel 30, the upright shaft 31 having been previously set in motion by starting the motor 62, which will cause said gear 29 to rotate, and thus impart rotation to the crank arm 26, which in turn will operate the rocker arm 20 and rack bar 19, and thus in an obvious manner impart motion to the dasher mechanism within the tub. At the same time that the washer mechanism is being operated, the wringer may also be simultaneously operated, and this is effected by manipulation 25 in suitable direction of the handle 71 mounted upon the wringer, which movement of the handle will either raise or lower the sliding carriage 67, thus carrying with it the arms 75 and 76, which as seen in Fig. 30 1 correspondingly move the sleeve 58 upwardly or downwardly on the shaft 31, the particular direction being determined by the direction of the movement of the handle 71. For the sake of illustration, we will assume that the sleeve 58 has been moved upwardly which will, as seen in Fig. 2, place the worm teeth 59 in engagement with the gear 77, which will impart motion to the wringer rolls in the appropriate direction.
- 35 It is also to be noticed that during the movement of the carriage 67 upwardly, the rod 78 shown in Fig. 3 will be carried upwardly therewith, which will result, due to the connection heretofore described of this rod with the drain board, in the tilting of the drain board 80 to the proper inclination with respect to the rolls to carry off the water from the rolls in the proper direction. Should it be desired to reverse the direction of the rotation of the rolls, this can be readily accomplished by moving the handle 71 to the other extreme of the quadrant, which will lower the sliding carriage 67, and in turn the sleeve 58, thus throwing the worm teeth 45 50 55 60 into engagement with the gear 77. Since the teeth 59 are right hand and the teeth 60 left hand, it will be obvious that this last stated operation will reverse the direction of rotation of the rolls, and due to the connection hereinbefore set forth of the rod 78 with both the drain board 80 and the sliding carriage 67, the inclination of the drain board will automatically be changed simultaneously with the shifting of the gears and changing of rotation of the rolls. It is, of

course, obvious that both the wringer and the washing machine may be operated simultaneously or separately at will.

If it is desired to change the position of the wringer, this may be accomplished by moving the handle 49, see Figs. 1 and 9, and withdrawing the projection 52 from engagement with the socket 55, which will leave the sleeve 45, by which the wringer is carried, free to rotate. The wringer may then be swung into the desired position, after which it may be there locked by inserting the projection 52 into the nearest socket at the new position. Attention is called to the fact that the wringer rolls may be operated equally well and also simultaneously with the washing mechanism no matter what position the wringer occupies, and that this motion may also take place during the time that the wringer is being swung from one position to another, since the driving connection of the wringer and the washing mechanism is entirely independent from the mechanism by which the adjustment of the wringer is effected. As already pointed out, if it is desired to drain the water from the tub, this may be easily accomplished by tilting the tub and placing the free end of the bar 12 in engagement with the aperture 11, which will hold the tub in such tilted position.

I consider the mounting of the motor at the top of the shaft as an important feature. In this location, it is removed from danger of moisture from the tub, and is much more accessible to the operator than if placed beneath the stand.

In order to permit of movement of the bevelled blocks 89 and 90 towards or away from each other, the lower laterally extending portion 93' of the handle 93 is provided with the elongated slot 93^a, within which slide the neck portions of the screws 93^b.

Having now described my invention, I claim:

1. In combination, a stand having an upright shaft thereon, means for rotating said shaft, a wringer operatively connected with said shaft, a tilttable drain on the wringer, and means for throwing the rolls of said wringer into forward, backward or neutral engagement with said shaft and simultaneously tilting said drainboard to the proper angle with relation to said rolls.

2. In combination, a stand having an upright shaft thereon, a wringer mounted on said stand to swing about said upright shaft as an axis, and having a pair of rolls, a gear connected with one of said rolls, a sleeve splined on said shaft and having right hand threads on one end, left hand threads on the other, and a depression between said threaded portions, and means for sliding said sleeve longitudinally of said shaft, whereby to place said gear in operative connection

with said right or left hand threads or opposite said depression, as desired, whereby said wringer rolls may be operated in either direction or remain stationary as desired.

3. In a wringer, a frame, a pair of rolls in said frame, a drive shaft, a drain board tiltably mounted on said frame, a gear on one of said rolls, a sleeve splined on said shaft, 10 oppositely inclined worm teeth on the respective ends of said sleeve for engagement with said gear, and means on said frame for simultaneously shifting said sleeve on said shaft and tilting said drain board.

15 4. In an apparatus of the kind described a frame, a pair of rolls in said frame having reversing mechanism, a drainboard tiltably mounted in said frame beneath said rolls, and means for automatically tilting said 20 drainboard to any one of a plurality of positions when the rotation of said rolls is reversed, said tilting means comprising a device positively connecting the drainboard and the roll reversing mechanism.

25 5. In a wringer, a frame, a pair of rolls in said frame, a gear on one of said rolls, a drain board tiltably mounted in said frame beneath said rolls, a drive shaft, a double worm sleeve slidably keyed on said shaft for 30 engagement with said gear, a sliding carriage on said frame operatively connected with said sleeve and said drain board whereby they may be simultaneously operated.

35 6. In a wringer having a pair of co-operating rolls, means for driving said rolls in either forward or reverse direction, a drain board adapted to be inclined according to the direction of rotation of the rolls, and means connecting the drain board with the 40 means for reversing the direction of rotation of the rolls so that the two will always be simultaneously reversed.

45 7. In a wringer having a pair of reversible co-operating rolls, means for driving said rolls, means for reversing the rotation of said rolls including a slide, a drain board beneath the rolls adapted to be inclined according to the direction of rotation of the rolls, and means connecting the drain board 50 and slide so that when the rolls are reversed the drain board will also be reversed.

55 8. In a wringer, a frame, a pair of rolls, a gear on one of said rolls, a drive shaft on which is slidably mounted a double worm sleeve for engagement with said gear, a drain board tiltably mounted in said frame, a carriage slidably mounted on said frame and having arms for transmitting sliding motion to said sleeve, a connecting rod connecting said carriage and one side of said 60 drain board, and means for transmitting sliding motion to said carriage, whereby the direction of rotation of said rolls may be reversed as desired, and said drain board 65 tilted simultaneously therewith.

9. In apparatus of the class described, a wringer having a frame, a pair of rolls, means for rotating said rolls, and means for adjusting the tension between said rolls, said means comprising a screw having right 70 and left hand threads thereon, bevelled blocks carried by said screw and bevelled means engaging said blocks respectively, whereby upon rotation of said screw the tension between said rolls will be regulated 75 as desired.

10. In apparatus of the character described, a wringer having a frame, a pair of rolls in said frame, a supporting shaft for one of said rolls, bearings for the shaft, 80 coil springs extending longitudinally in opposite frame members, engaging at each end of one of said rolls the bearing for the supporting shaft carrying the same, a member mounted in said frame to move toward and 85 away from said rolls and having wedge-faced means engaging said springs to compress the same, a screw in said frame parallel to said member and wedge-faced elements carried by said screw and slidably 90 engaging with said wedge-faced means to move the same and the member to and from the rolls whereby the tension in said coil springs will be simultaneously adjusted.

11. In a wringer mechanism, a frame, a pair of rolls in said frame having reversing mechanism, a drain board beneath said rolls and tiltably mounted in said frame, and means for tilting said drain board into various positions when the roll reversing mechanism is actuated, said tilting means including a rack and pinion and a link connecting the rack to the drain board.

100 12. A wringer having a frame, a pair of rolls in said frame, a coil spring engaging 105 at each end of one of said rolls a bearing for the supporting shaft carrying said roll, and means for simultaneously increasing or decreasing the tension in each of said springs, said means including members having pairs of bevelled cooperating surfaces, two of said members being operable in opposite longitudinal directions to move the other two transversely of the direction of motion of the two first named, and a single 110 screw for simultaneously operating the members carrying said pairs of bevelled surfaces, and means to abruptly separate sideways two of the members carrying said bevelled surfaces from the other two when 115 desired to quickly release the tension between said rolls.

125 13. In apparatus of the class described, a wringer having a pair of rolls, a spring adjacent each end of one of said rolls, a bevelled block bearing against each of said springs, a second bevelled block adjacent each of said first mentioned blocks, the bevelled portions of said adjacent blocks interengaging, and means for rotating said second 130

- mentioned blocks out of engagement with said first mentioned blocks, whereby the tension in said springs may be abruptly diminished and said rolls quickly separated.
- 5 14. In a device of the class described, a wringer having a pair of rolls rotatable in either direction, a tiltable drain, and means for causing the wringer rolls to be operatively connected to their driving mechanism or to be disconnected therefrom, said means also simultaneously tilting the drain in accordance with the direction of rotation of the rolls.
15. In a device of the character described, a frame, a driven element mounted thereon, a tiltable member below the driven element, driving means for the driven element, means for connecting the driven element to the driving means in different operative relations, and actuating means operatively connecting the tiltable member with the last named means, whereby, when said connection shifting means is actuated, it simultaneously tilts the tiltable member and changes the connection between the driving means and the driven element.
16. In a wringer mechanism, a tiltable drain board, means connected thereto for tilting the drain board including a rack, means for actuating said rack, wringer rolls, means for rotating said rolls in either of two directions, or permitting them to remain idle, and means connecting the rack and the roll operating mechanism, so that tilting of the drain board and reversal of the wringer rolls are simultaneously effected.
- In witness whereof, I hereunto subscribe my name to this specification.
- BERT A. STOCKING.
